NEGLIGEE

Filed April 4, 1935

FIG. 1

FIG. 2

Pauline Schmittman
INVENTOR

UNITED STATES PATENT OFFICE

95,709

DESIGN FOR A NEGLIGEE

Pauline Schnittman, New York, N. Y.

Application April 4, 1935, Serial No. 56,203

Term of patent 3½ years

To all whom it may concern:

Be it known that I, Pauline Schnittman, a citizen of the United States of America, residing in Manhattan, in the county of New York and State of New York, have invented a new, original, and ornamental Design for a Negligee, of which the following is a specification, reference being had to the accompanying drawing, forming part hereof, wherein,

I claim:

The ornamental design for a negligee, substantially as shown.

PAULINE SCHNITTMAN.
